APPARATUS FOR STOKING FURNACES

Herman L. Kraeft, Cleveland, Ohio, assignor to
The Murray Ohio Manufacturing Company,
Cleveland, Ohio, a corporation of Ohio

Application January 4, 1933, Serial No. 650,095

7 Claims. (Cl. 110—115)

This invention is concerned with a stoker mechanism primarily adaptable for overfeed stokers, and particularly to overfeed stokers for domestic heating furnaces, and to carry out my method of fueling a furnace described in my Patent No. 2,027,485 issued January 14, 1936, and of which this application comprises a continuation in part.

The general object of the present invention is 10 the provision of a coal stoking mechanism which will be readily adaptable to various types of domestic furnaces, and which will be efficiently responsive to the functioning of thermostatic controls while being utilizable for the feeding of a 15 wide range of fuels. To this end the present invention is concerned primarily with a stoker mechanism adaptable to the stoking of vapor, steam and hot air domestic furnaces, regardless of the variations in the design of the furnace 20 structure and dimensional variations in the fire-boxes of such furnaces. The invention embodies a mechanism which can be quickly and readily installed in cooperative relation with a furnace without necessitating any serious alterations in 25 the furnace structure.

A further object of my invention is the provision of a stoker mechanism which will function in such manner as to eliminate the danger of 30 fire hazards.

A still further object of my invention is the provision of a compact stoker mechanism which may be easily and quickly brought into cooperative 35 relation with the fire door of the furnace structure or be removed therefrom manually and without requiring any disorganization of the elements comprising the stoker mechanism.

A still further object of my invention is the provision of a stoker mechanism having a fuel agitating hopper which will prevent arching of 40 the fuel while in the hopper.

A further object is the provision of an improved overhead suspension for a stoker mechanism.

Other objects and purposes of my invention, as 45 embodied in the mechanism shown in the drawings, will hereinafter become apparent from the following description, which refers to said drawings and the essential objects of the invention are summarized in the claims.

In the drawings, Fig. 1, is a side elevation of a 50 domestic heating furnace of the hot air type, showing my stoker mechanism associated therewith, certain parts of the furnace being broken away to more fully illustrate the stoker mechanism; Fig. 2, is a perspective view of the stoker

mechanism, removed from association with the fire door of the furnace; Fig. 3 is an enlarged front elevation of part of the furnace and stoker mechanism shown in Fig. 1, certain parts being broken away to illustrate the internal construction thereof; Fig. 4, is a fragmentary longitudinal sectional elevation through part of the stoker mechanism in cooperative relation with the fire door of the furnace, the plane of the section being indicated by the offset line 4—4 of Fig. 3; Fig. 5 is a fragmentary horizontal section through part of the stoker mechanism, taken substantially along the line 5—5 of Fig. 4; Fig. 6, is a sectional view taken substantially along the line 6—6 of Fig. 4; and Fig. 7 is a sectional view of a speed reducing device comprising part of the stoker drive; Fig. 8 is an enlarged view of a damper mechanism, certain parts thereof being broken away to more clearly illustrate the internal construction; Fig. 9 is a section taken along the line 9—9 of Fig. 8; Fig. 10 is a section taken along the line 10—10 of Fig. 9; Fig. 11 is an enlarged section taken substantially along the line 11—11 of Fig. 1 illustrating my improved manner of stoker suspension.

My invention is shown as being embodied in a unitary stoker and blower mechanism, which may be suspended by an overhead trolley, whereby the fuel discharge end of the stoker mechanism may be inserted in the fire door of the furnace or withdrawn therefrom by shifting the stoker mechanism along a supporting trolley rail. The stoker mechanism is provided with a revolving hopper of a substantial size, whereby a sufficient mass of fuel may be charged into the stoker to provide for about a twelve-hour fuel demand of the furnace during the very cold season.

In Fig. 1, I show a hot-air furnace 10, provided with the usual fire door frame 11, fire pit 12 and ash pit 13. The stoker mechanism comprises a substantially large coniform hopper 15, revolvably mounted upon a downwardly extending coal guiding chute in the form of a neck or base 16, which supports the hopper 15 with the axis thereof oblique to a horizontal plane. The base 16 is round at the top and of a rectangular shape at the bottom, and comprises a connecting passage way between the bottom opening of the hopper 15 and a rectangularly shaped fuel feed tube 45, attached to the bottom of the base 16.

To support the hopper, the base 16, (see Figs. 1, 3, 4 and 11) is provided with an annular outwardly extending flange 17, to which is attached a suspension frame comprising a pair of downwardly extending bars 18 and a pair of arcuately

shaped bars 19, a hopper bearing bracket 21 and straps 22. The bars 18, and 19 are attached at their upper ends to a trolley 23, by adjustable bolts 24 and 25, respectively. In Fig. 11, I show 5 associated with the stoker supporting mechanism, and particularly with the bolts 24 and 25, means for absorbing all vibration incident to the operation of the stoker when the stoker mechanism is in use. This means is illustrated in the form of 10 10 resilient cushions which take the entire weight of the stoker mechanism while the stoker is movably supported from a rail 30. The rail is suspended by strap members 26, which, at their lower ends are secured to the rail 30, while at the upper 15 ends thereof, suitable hanger formations are provided for engagement with bolts 27. The upper ends of the bolts 27 are surrounded by resilient sleeves 28, preferably rubber. These sleeves bear against brackets 29, which are connected in any 20 suitable manner to the ceiling structure. In similar manner I provide resilient sleeves 32, surrounding the upper ends of the bolts 24 and 25, and bearing upon the lower ends of suitable trolley wheel brackets 41, that are secured in spaced 25 relation by the trolley 23. The upper ends of the brackets 41, extend over the rail 30 and support trolley wheels 42. I prefer to mount the rail 30 substantially horizontal and through adjustment of bolts 27, the inner end of the rail 30, that 30 is, the end of the rail toward the furnace, is then dropped slightly below the opposite end, whereby the rail slopes toward the furnace, thus causing the stoker mechanism to have a tendency to remain in a forward or cooperating position relative to the firebox door. By reason of the resilient 35 suspension described, the entire mechanism may be slightly swayed in manipulating the stoker mechanism relative to the firebox door. I provide the trolley mechanism with a locking lever 44, so arranged that the lever may be swung into a camming or locking engagement with the rail to hold the stoker mechanism in a remote position from the furnace when it is desired to inspect the firebox of the furnace.

45 I will now describe my manner of revolvably mounting the hopper, and particularly the construction of the lower end of the hopper. As shown in Fig. 4, the lower end of the hopper is provided with an annular outwardly extending 50 flange 35, positioned slightly above the flange 17. The flange 35 comprises both a bearing plate for the lower end of the hopper and part of the mechanism which permits an intermittent revolving movement of the hopper when the feed plunger is in motion. To decrease the attendant 55 friction I provide, as shown in Fig. 3, flanged rollers 37, which engage the flange 35. These rollers are spaced substantially ninety degrees apart, and are supported by stud bolts 38, fixed 60 to the flange 17. These bolts also serve to rigidly secure the lower ends of the straps 22, and bars 18, to the flange 17. The hopper bearing bracket 21 is provided with two spaced-apart rollers 21a, which bear against a bearing band 15a, secured 65 to the hopper wall. It will thus be apparent that the hopper 15 is supported upon six rollers, namely two rollers 21a, and four rollers 37.

70 The fuel feeding mechanism comprises the rectangular tube 45, which is attached to and supported by the base 16 in any suitable manner. Disposed within the tube and slidably arranged 75 therein is a rectangular plunger 46, which is arranged to rest immediately beneath the outer edge of the base 16. The plunger 46 is provided with a bracket 48, having a wrist pin 49, the wrist pin

being engaged by the inner end of a fork shaped connecting rod 50. The outer end of the connecting rod 50 is operatively attached to a crank 51 carried by rotatable disc 52. The disc 52 is mounted upon the end of a gear shaft 53, whereby 5 rotation of the shaft will cause a reciprocating movement of the plunger 46 within the feed tube 45. The travel of the plunger is dependent upon the radial displacement of crank 51 relative to the center of the shaft 53.

10 The shaft 53 comprises part of a gear reduction mechanism housed within a casing 54, the casing being attached to the outer end of the feed tube 45.

The gear reduction mechanism is best shown in Fig. 7 and comprises an internal gear 140, secured to the casing 54, in cooperative relation with a gear 141, which is loosely mounted upon an eccentric 142, comprising part of a driving shaft 143. The driving shaft 143 is driven by a 20 pulley 11. The gear 141 has attached thereto a spur gear 146, which meshes with an internal gear 147, fixed to a spider 148. The spider 148 is fixed to the driven shaft 53 by a pin 149, extending therethrough. The ratio between the 25 gears 140 and 141 is forty-one to forty-three respectively, and the ratio between the gears 147 and 146 is forty to forty-two respectively. The rotation of the shaft 143 causes the double gear 141—146 to have a slight eccentric motion relative to the axis of the shaft 143, thus causing the gear 141 to have a one tooth displacement relative to the fixed internal gear 140 upon each revolution of the shaft 143. The gear 146, by reason of the fact that it is fixed to the gear 141, thus 30 drives the internal gear 147 and shaft 53. The shafts 53 and 143 may be supported with suitable bearings. To reduce frictional losses I provide a ball bearing mounting 160 and a sleeve bearing 161 to support the shaft 143, the sleeve bearing 40 161 being mounted in a suitable bore, formed in the inner end of the shaft 53. Bearings 164 and 165 serve to rotatably support the shaft 53 and the attached spider 148.

45 Adjustment of the crank pin 51 relative to the center of the shaft 53 to vary the stroke of the plunger, is afforded by the fact that the crank pin has the crank end thereof eccentrically formed relative to the threaded bolt portion 51a thereof (see Fig. 7). A clamping 50 nut 51b serves to secure the pin 51 in position upon the disc 52 when the desired adjustment of the plunger stroke has been obtained. It should be noted that in Fig. 7 I provide the pin 51 with a knob 56 to facilitate adjustment of the pin. In the embodiment illustrated the stroke of the plunger may be varied from one inch to one and one-half inches.

55 In Fig. 4 I have shown a tray 58, which is 60 slidably supported by transversely disposed guides 59, mounted on the bottom wall of the feed tube 45, adjacent a slot 60 which extends substantially across the bottom wall of the tube immediately adjacent the outer edge 46a of the 65 lower part of the plunger structure, whereby any coal dust which becomes lodged along the side and bottom walls of the plunger will escape into the tray 58. The slideable mounting of the tray permits removal of such dust from time to time.

70 I arrange, at the forward or fuel engaging face of the plunger 46, a fuel agitator which 75 rides along the bottom wall of the tube 45, for substantially its entire fuel conducting length. This agitator comprises a metallic feeder 80, 75

provided with a series of transverse strips or teeth 81, shaped to simulate ratchet teeth, whereby, upon the forward fuel feeding movement of the plunger 46, the teeth 81 engage the lowermost particles of the fuel and thus tend to move the entire column of fuel within the conduit. The feeder 80 covers substantially one-third of the area of the bottom wall of the tube and as the plunger moves forwardly assists the plunger in shifting the column of fuel forwardly. By reason of the shape of the teeth 81 the feeder has little tendency to move the coal rearwardly upon the return stroke of the plunger. The feeder and the coal thereon are supported by the bottom wall of the tube 45, to which end I provide a loose connection between the plunger and the feeder 80. Such connection may comprise vertically extending plates 80a secured to the plunger face, and loosely engaging flanges 82a formed on a bracket 82 comprising part of the feeder 80.

The mechanism for intermittently moving the hopper will now be described. The hopper 15 is revolved by a pawl 84, pivotally attached at its outer end to a bracket 85, rigidly secured to the connecting rod 50 at such operative position that the pawl 84 may extend upwardly and outwardly to engage, in step by step movements, openings 35a, equidistantly spaced in the hopper flange 35. It will be apparent from Figs. 3 and 4 that revolving motion is imparted to the hopper during the return stroke of the plunger; thus voids momentarily created in the feed tube 45 by reason of the forward fuel stroke of the plunger will be eliminated by the agitation of the body of fuel upon the return stroke of the plunger. A detent pawl 87 is provided at the opposite side of the flange 35 for preventing reverse movement of the hopper.

40 A fuel flipper mechanism is disposed at the extreme forward or discharging end of the fuel feeding tube 45 and is arranged within a housing, whereby, when the entire stoker mechanism is shifted to operative position relative to the
45 fire door, the flipper mechanism, while being disposed immediately adjacent the front wall of the fire box, will be protected by the housing. The proportioning and design of the flipper mechanism is such that large particles of fuel
50 cannot become lodged in any part of the mechanism which is exposed to the heat of the fire. The arrangement is also such that the stoker mechanism is readily adaptable to various sizes of fire door frames, which fire door frames may
55 vary from 9 to 15 inches in length and from 8 inches by 10 inches in height and breadth respectively. The mounting of the flipper housing is such that regardless of the width of the firedoor frame of the furnace the rotary flipper
60 member can always be adjusted to a juxtaposed position relative to the fire bed edge.

This fuel flipper mechanism comprises a revolving cylinder or flipper 70 (Figs. 4, 5, and 6) mounted upon a shaft 72. The shaft 72 has a sprocket wheel 73 mounted on an extending end thereof, and this sprocket wheel is driven by a suitable chain 71. The chain 71 is driven by a sprocket wheel 201 secured to a rotatable sleeve 202, which is mounted upon an adjustable stud shaft 200. The sleeve 202 has also mounted thereon, a step pulley 204, driven by a belt 205, which belt is driven by a step pulley 132 mounted upon a motor shaft 124. The stud shaft 200 is adjustable to permit adjustment in the length of the feed tube, and thereby meet

varying installation conditions, and to enable the rotary flipper 70 to be disposed adjacent the edge of the firepit within the firedoor frame of the furnace. Accordingly, as shown in Figs. 4 and 5, I provide an arcuate slideway formation for adjusted anchorage of the stud shaft 200, upon the side wall of the feed tube. This anchorage may comprise a plate 208, to which the inner head 200a of the stud shaft may be clamped by a nut 206. Thus the shaft can be adjusted to swing its center about the center line of the motor shaft 124, should the length of the feed tube be increased or decreased to meet installation conditions. It will be apparent that two different feeds of the flipper 70 are obtainable through the step pulleys 132 and 204, and other feed changes may be made by changing the size of the sprocket wheel 73.

The flipper 10 is of substantially the same length as the width of the fuel tube 45 and the surface design thereof is of a particular functioning shape to be described in greater detail hereinafter, and is provided with an enclosing casing comprising an arcuately formed guard 74, having end walls 75 to which are attached bearings 76 for rotatably supporting the shaft 72 and flipper cylinder 70 in an operative position adjacent to and immediately below the inner discharge end of the feed tube 45. To support the casing comprising the guard for the flipper 10, I provide a box-shaped housing 90, arranged to telescope with a second box-shaped housing 91, the latter being secured to a door closure plate 92 formed of any suitable material. The closure plate may be of such dimension as to comprise a closure for the largest size doors to be found on domestic furnaces of whatever type. The side walls 75 of the flipper casing are flanged, as indicated at 96 (Fig. 5) for rigid attachment to the housing 90, and the width and height of the housing 90 is such as to provide sufficient space for the enclosure of the sprocket wheel 73, as well as the bearings 76. The side walls 75 of the flipper casing extend upwardly and are attached to a plate 97, which is flanged at the outer edge thereof for attachment to the housing 90 as shown at 98 (Fig. 4). The plate 97 is inclined downward and forward from the top wall of the housing 90 to serve as a fuel guide to deflect downwardly any heavier particles of fuel which might be flipped upwardly at too great an angle to escape the inner edge 99 of the fire door frame. The inner portion 97a of the plate 97 engages the top outer surface of an extension tube, 100, which comprises the inner portion of the fuel feed tube 45. The top wall 90a of the housing 90 extends between the portion 97a of the plate 97 and the top wall 91a of the telescoping housing 91. The tube 100 is shaped to telescopically embrace the outer surfaces of the inner end of the tube 45, whereby the tube 100 may be of any desired length to suit the particular requirements of the installation. I provide bolts 101 for securing the tube 100 firmly to the inner end of the tube 45. I also provide the housing 90 with binding lugs and wing nuts, as indicated at 102, which lugs extend through slots 104 and 105 formed in the side walls of the housing 91, and clamp the housings 90 and 91 firmly together in any adjusted position.

I also provide an adjustable horizontally disposed ledge 110, which in function comprises an extension of the bottom wall of the fuel feed tubes 75

45 and 100. This ledge 110 serves to predetermine the falling movement of the coal particles as the same escape thereover upon the revolving flipper 70. The ledge as shown in Fig. 4 is provided with downwardly extending slotted flanges 110a through which clamping bolt 111 extends to secure the ledge in any desired adjusted position. Graduations, as indicated at 112 may be provided on one of the end walls 75 of the flipper 10 per casing to indicate the degree of adjustment of the ledge 110 relative to a vertical plane extending through the axis of the flipper 70.

The surface of the flipper 70, as shown in the drawings, is provided with blades 70a, preferably 15 integrally formed about the perimeter of the body of the flipper and tapering toward the center thereof, thus imparting to the fuel particles not only an outward throw from the discharge end of the tube, but also an angular throw relative to the tube center line. I also form the surface 70b of the flipper, as shown in Fig. 4, so that when the stoker mechanism is at rest any coal particles, which may drop from the inner end of the tube cannot become lodged within 20 the semi-circular arcuate terminus of the casing 74. I also provide the casing 74 with a chute 74b, extending downwardly from its forward terminus 74a to guide any light particles of fuel which might fall when the stoker is at 25 rest, so at such times no fuel particles in the stoker mechanism are exposed to the heat of the fire bed, which particles otherwise might become ignited and cause the ignition of the fuel which is at rest within the feed tube.

30 It should be noted that the relationship of the flipper 70 to the inner or discharge end of the fuel feed tube and to the rim of the fire pit is such that the desired flipping action on the fuel particles can be obtained without causing 35 undue agitation of the fuel particles. The plunger makes from 1 to 3 strokes per minute and the fuel displacement along the tube is from one inch to one and one-half inches per plunger stroke. The size of the flipper 70 is such that 40 it can be disposed immediately beneath and adjacent to the discharge end of the tube in such a position that the flipping action thereof will not cause the coal particles to be thrown too violently. The dimensions of the tube in cross- 45 section are approximately four inches high and six inches wide and the flipper extends the full width of the tube. The dimensions of the flipper thus will be apparent. The speed of the flipper can be varied from three hundred R. P. M. 50 to about nine hundred R. P. M., and the correct speed will be dependent upon the size of the fire bed and the physical characteristics of the fuel to be fed thereto.

55 It will be apparent from the foregoing description of the flipper, the housings therefor, the adjustable nature of the tube structure extending between the flipper housing and the hopper mechanism, that the flipper can always be positioned at the desired point relative to the fire- 60 bed pit or firebox of the furnace, while the distance of the hopper mechanism from the front of the furnace, may be varied to meet any physical environmental condition, such as piping, sewer connections, variation in ceiling structure, etc., 65 without in any way disrupting the interfunctional relationship of the fuel feeding element and the flipper mechanism.

70 I provide a blower mechanism which may be operated only when the stoker mechanism is functioning to feed fuel to the fire bed. This blower

mechanism may comprise the conventional type of blower casing 120 and fan 121, the casing 120 being secured to the frame of the motor 123, and the fan 121, being secured to one end of the motor shaft 124. Depending from blower casing 120 5 is a flexible tube 125, which extends downwardly and through a suitable opening 127, formed in the ash pit door 126 of the furnace structure. The blower casing 120 is provided with an air inlet openings 180 (Figs. 3 and 4) and the volume 10 of air passing therethrough is regulated by the distance between an adjustable disc 181 and the wall of the casing adjacent the opening 120. The disc is threaded upon a stud 182 carried by the blower casing. The volume of air required is determined by the size of the fire bed, the burning characteristics of the fuel used and the heat delivery demands upon the furnace. Hence, adjustment of the disc 181 toward or away from the air inlet opening of the blower casing will be determined by operating trials of the stoker mechanism at the time of installing the same.

15 While the disc 181 just described affords some means for controlling the action of the blower upon the firebed when the stoker is in operation, 20 I find it to be advantageous to provide a pneumatically operated damper in the air duct 125. This damper is arranged to open under the influence of the blower and to automatically shut 25 when the blower is not in operation, thereby preventing the influence of a natural draft upon the firebed, particularly under weather conditions when high winds are prevailing. This damper is attached to the ash pit door and may comprise, 30 as shown in Figs. 8, 9, and 10 a tubular sleeve 35 212, of sufficient diameter to conveniently telescopically receive the lower end of an elbow fitting 213, the fitting being attached to the end of the duct 125. The sleeve 212 may be secured to the ash pit door 126 by bolts 216. The damper 40 comprises a disc-shaped light metal valve 220 and is secured to a pin 221 journalled in the sleeve 212 to swing about an axis disposed below the center thereof. An outer end 221a of the pin 221 is bent normal to the axis of the pin to form an arm 45 upon which is adjustably mounted a weight 225. The weight acts to swing the valve and cause the edges thereof to abut a shoulder 226, disposed within the sleeve 212. I also provide an adjustable stop in the form of a screw 228, mounted on 50 the sleeve 212, in the path of the arm 221a, whereby the amount of the opening movement of the valve 220, under the influence of the blower, can be adjusted.

55 The motor 123 may be suitably mounted in an inverted position upon a bracket 128, adjustably secured by bolts 129 to a depending bracket 130, secured to the bottom wall of the fuel feed tube 45 at a position to permit practical driving connections between the pulley 132, mounted upon 60 one end of the motor shaft 124, and pulley 77, mounted upon the shaft of the gear reduction mechanism. A belt 134 serves to drivingly connect the pulleys 132 and 77.

65 My prior experience with stokers of the overfeed type has disclosed that a feed tube carrying fuel cannot be extended into the fire box without attendant difficulties. Under such a condition, the fuel when in the tube has a tendency to coke, thus liberating tar and other sticky components 70 of the average fuel. Likewise, there is always present a fire hazard under such circumstances. It will be apparent from the stoker disclosed in the drawings that my apparatus for the overfeed stoking of a furnace can be successfully used on 75

different types of domestic heating furnaces and the difficulties and dangers above mentioned are avoided.

Likewise, my improved stoker is practical from 5 a commercial viewpoint, in that regardless of variations in the width of the fire door frame 11, the inner end of the tube and the flipper mechanism can always be adjusted to the proper relationship relative to the rim of the fire pit by reason of the 10 telescoping construction of the flipper housing with the feed tube 45 and by reason of the fact that I provide the fuel feeding tube 45 with the extension tube 100, thus making the installation of the stoker mechanism readily adaptable to 15 various furnace structures. It will be apparent that the only alteration in the structure of the furnace proper would be to swing open the furnace door and to form an annular opening in the ash pit door for the reception of the lower end of 20 the blower duct 125.

My stoker has been used with anthracite fuel of the so-called pea size, as well as with anthracite culm and bituminous slack coals of both high and low grades, and by reason of the manner in 25 which I control the application of these fuels to the top of the fire bed, I have been able to meet widely varying conditions.

It will be apparent to those skilled in the art 30 that the stoker mechanism as illustrated in the drawings may be constructed primarily from sheet metal and preferably ingot iron sheets, which will resist corrosive action, and the entire arrangement will be readily responsive to the operative regulation of any of the standard thermostatic control devices now on the market.

I am aware that flipper mechanism for throwing coal onto a fire bed have been proposed heretofore. Such mechanisms have usually been associated with some form of blower means functioning through the fire door. I have devised a 40 flipper mechanism which avoids the use of a blower and I thus avoid the escaping of partially burnt coal dust up the chimney. Protracted testing of my stoker demonstrates the importance of agitating the mass of fuel while removing measured quantities thereof and the ledge principle of fuel escape makes the controlling of the flipping action practical, whereby the powdered portion of the fuel will not be unduly agitated to the extent that the same would be caused 45 to escape up the flue without being burned. The apparatus has been quite successful in stoking a variety of fuels, while maintaining a proper fire bed that will produce very low ash and low fuel 55 losses.

I claim:

1. In a coal feeding mechanism the combination of a coal hopper, a substantially horizontally disposed fuel feeding tube beneath the hopper 60 and provided with a discharge opening means extending between hopper and tube affording a fuel passageway, a plunger in the tube disposed forwardly of the passageway adapted to feed fuel through the tube, a speed reduction mechanism 65 mounted on one end of the tube, mechanism extending between the speed reduction mechanism and the plunger for imparting limited reciprocating movements to the plunger, an electric motor mounted on the tube, a rotary fuel flipping mechanism mounted below the tube adjacent the inner 70 end thereof and disposed beneath the fuel discharge opening of the tube, and means drivingly connecting the motor to the rotary fuel flipping mechanism and to said plunger actuating mechanism.

2. In a stoker mechanism a unitary structure adapted to be suspended from above, whereby the entire mechanism may be mounted upon a trolley to permit the shifting of the stoker mechanism to and from the fire door of a heating furnace, said 5 stoker mechanism having a fuel feeding tube adapted to be projected into the fire door of the furnace and provided with a discharge end, a fuel flipping mechanism adapted and arranged to be disposed at the margin of the fire bed of the 10 furnace and adapted and arranged to flip the fuel inwardly over the fire bed as the fuel falls from the discharge end of said tube, means for shifting the fuel longitudinally of the tube including a plunger and associated mechanism for 15 reciprocating said plunger, a motor supported by the tube, driving connections between the plunger reciprocating means and the motor and between the motor and the flipping mechanism, whereby the flipping mechanism is operated only when the 20 plunger is being operated, and a blower mechanism associated with said motor and including an air duct adapted to extend to the furnace ash pit when said fuel feed tube is operatively positioned with its inner end within the fire door frame of 25 the furnace.

3. In a coal feeding mechanism the combination of a revolvable hopper, a substantially horizontally disposed fuel feeding tube arranged beneath the hopper and provided with a discharge 30 opening, means connecting the hopper and tube and affording a passageway therebetween, a plunger in the tube disposed forwardly of said passageway, a speed reduction mechanism supported by one end of the tube, mechanism to drivingly 35 connect the speed reduction mechanism with the plunger, mechanism to drivingly connect the speed reduction mechanism with the hopper, an electric motor supported by the tube, a fuel flipper member mounted adjacent the inner end of 40 the tube and disposed beneath the fuel discharge opening of the tube, said member being rotatable, and means drivingly connecting the motor to the rotatable member and to said speed reduction unit.

4. In a coal feeding mechanism, the combination of a hopper, a substantially horizontally disposed fuel feeding tube beneath the hopper and provided with a discharge opening, there being a passageway between the tube and the hopper, a 50 plunger in the tube disposed forwardly of the passageway, a speed reduction mechanism, a drive crank mechanism interconnecting the speed reduction mechanism and the plunger, a housing structure supported by the tube adjacent the inner end thereof and disposed beneath the fuel discharge opening of said tube, a rotary fuel flipping mechanism enclosed within said housing, an electric motor supported by the tube, and means drivingly connecting the motor to the fuel flipping mechanism and to the speed reduction mechanism, and said housing comprising a heat insulating means whereby the flipping mechanism may be operatively positioned adjacent a fire bed.

5. In a stoker mechanism a unitary structure 65 adapted to be suspended from above, whereby the entire mechanism may be mounted upon a trolley to permit the shifting of the stoker mechanism to and from the fire door of a heating furnace, said stoker mechanism having a fuel feeding tube 70 adapted to be projected into the fire door of the furnace and provided with a discharge end, a fuel flipping mechanism adapted to flip the fuel inwardly over the fire bed as the fuel falls from the discharge end of said tube, said flipping mecha- 75

- nism including a rotatable member having impellers formed about the circumferential surface thereof, said rotatable member being supported at the inner end of the tube, means for shifting the fuel longitudinally of the tube including a plunger and associated mechanism for reciprocating said plunger, a motor supported by the tube, driving connections between the motor and the plunger reciprocating mechanism and between the motor and said rotatable flipping mechanism to operate the flipping mechanism only when the plunger is being operated, and a blower mechanism associated with said motor and including a downwardly extending air duct, the lower end of which is adapted to extend to the furnace ash pit when said fuel feed tube is operatively positioned with its inner end within the fire door frame.
6. In a coal feeding mechanism, the combination of a coal hopper, a substantially horizontally disposed fuel feeding tube arranged beneath the hopper and provided with a discharge end having a fuel discharge opening therein, means connecting the hopper and tube and affording a fuel passageway between the hopper and the tube, a plunger in the tube and operable to shift fuel from said passageway to the discharge end of the tube, a speed reduction mechanism, a crank mechanism extending between the speed reduction

mechanism and the plunger for imparting limited reciprocating movements to the plunger, an electric motor, a rotatable fuel flipping member mounted below the tube adjacent the inner end thereof and disposed beneath the fuel discharge opening of the tube, and means drivingly connecting the motor to the rotatable member and to said speed reduction mechanism.

7. A stoker mechanism adapted to be shifted to and from a furnace fire door, said stoker mechanism having a substantially horizontal fuel feeding tube adapted to be projected into the fire door of the furnace and having a discharge end, a fuel feeding plunger disposed in the tube, a fuel flipping mechanism adapted and arranged to flip the fuel inwardly over the fire bed as the fuel falls from the discharge end of said tube, means for shifting the fuel longitudinally of the tube, a motor supported by the tube, a driving connection between the motor and the plunger and between the plunger and the fuel shifting means, whereby the fuel shifting means is operated only when the plunger is being operated, and a blower mechanism operatively associated with said motor and including an air duct, the lower end of which is adapted to extend to the furnace ash pit when said fuel feed tube is operatively positioned with its inner end within the fire door frame.
